UNITED STATES PATENT OFFICE.

JEAN GUSTAVE FALLOU, OF PARIS, FRANCE, ASSIGNOR TO L'UNION GENERALE D'ELECTRICITE, OF PARIS, FRANCE.

FREQUENCY REDUCING ARRANGEMENT.

Application filed November 8, 1926, Serial No. 147,143, and in France January 19, 1926.

My invention has for its object an arrangement allowing to reduce the frequency of an alternating current to a secondary frequency which is a given fraction of the primary frequency. This is of great interest for radiocommunication when it is desired to transmit or to receive waves at a frequency lower than that of the primary oscillations.

10 Generally speaking it can be used in any electric circuit comprising a generator, a motor and a measuring instrument each time it is necessary to provide this circuit with a reduced frequency current.

15 Up till now this frequency reduction has been obtained only through rotating machines or by means of vacuum tubes. Now rotating machines can only be used for low frequencies and vacuum tubes cannot be used 20 otherwise than for very small powers.

According to my invention I reduce the frequency by making the primary oscillation act on an oscillating circuit the frequency of which is multiple and comprises a fundamental frequency and several harmonics one of which has the same frequency as that of the primary oscillation.

Under such conditions any phenomenon making this circuit oscillate freely will be 30 sufficient to allow the primary oscillation to keep up the oscillations of the said circuit, these oscillations comprising the fundamental frequency oscillations and their harmonics. Electric filters of any known type 35 allow an easy elimination of all the undesired oscillations, only the desired harmonic passing through the filter. Any oscillation 40 having the frequency of the fundamental oscillation of the oscillating circuit or of one of its harmonics can thus be obtained.

For instance a circuit of the kind described can be provided as explained herein-after by means of a circuit comprising an induction coil with a magnetic core. The 45 free oscillations may be excited with their harmonics in such a circuit by a sudden modification to the electric state of the said circuit, for instance by opening a switch in-

serted so as to short-circuit the induction coil.

The following explanations allow the means whereby this can be obtained to be readily understood with reference to appended drawings.

Fig. 1 is an explanatory diagram.

Fig. 2 is a diagram given by way of example of a form of execution of a frequency demultiplying arrangement.

Fig. 1 shows an oscillating circuit comprising in series a supply of alternating current of a frequency N , a condenser 2 having a capacity C , a switch 3 and an induction coil 4 of an inductance L and having no magnetic core.

The supply 1 being active and the switch 3 being first open, there will be produced on closing of the switch a varying voltage between the terminals of the condenser the value of which is the sum of—

1°/ a nonpermanent amount due to a damped free oscillation of the circuit the frequency of which is approximately

$$m = \frac{1}{2\pi\sqrt{LC}}.$$

This amount becomes equal to zero after a very short time which varies according to the damping factor i. e. double the ratio between the resistance and the inductance.

2°/ a permanent amount due to oscillations having the same frequency N as the supply.

If it is desired for the supply 1 to keep up continuously the free oscillations of the circuit which can be done only at the frequency m of these oscillations, it is necessary that the frequency N of the supply or of its harmonics should be equal to the frequency m of the free oscillations of the circuit. Otherwise stated, one should have $N=m$ or $KN=m$ (KN being the frequency of the N th harmonic when it exists).

This proves that the oscillations of a circuit having a frequency m cannot be kept up by an alternator for instance without a special arrangement unless the frequency N

of the said alternator is a submultiple of or is equal to the frequency of the waves it is desired to produce. Therefore a given circuit can only serve for transmitting the frequency of the source or a multiple thereof.

If in the diagram shown on Fig. 1 the induction coil 4 without a magnetic core is replaced by an induction coil provided with a magnetic core the size of which is such that 10 when the switch 3 is closed, the damped oscillations corresponding to the nonpermanent part of the voltage referred to hereinabove provide a current sufficient for bringing the magnetic core beyond saturation 15 point, the inductance of this coil will be constantly equal to L up to said saturation point after which it will change. The nonpermanent waves alluded to comprise in this case, according to well-known formulae a fundamental wave the frequency of which is 20

$$m = \frac{1}{2\pi\sqrt{LC}}$$

and several harmonics of this fundamental wave having a frequency equal to multiples of m .

It is easy to understand that if the frequency N of the supply 1 is equal to that of one of the harmonics of the fundamental wave which wave and harmonics are produced by the closing of the switch, the whole system comprising this wave and its harmonics will be kept up. A predetermined wave can be therefore selected, the other 35 waves being eliminated by suitable known electric filters and the remaining wave will have the desired frequency lower than that of the supply.

It is not necessary for the keeping up of 40 the oscillations that the current from the supply and the harmonic having the same frequency should be in phase. However if this were desired, the putting into phase could be easily provided by closing the 45 switch at the instant the supply current passes through zero.

Experience has shown the above theory to be correct and I have been able to keep up in a small-sized circuit fed by a 50 period 50 alternator oscillations having a frequency of $50/9$ of $50/4$ and of $50/3$; this latter frequency was kept up with a great steadiness and an output of about 17 watts.

By way of example I have described hereinbelow a diagram of a form of execution of my invention, this diagram being shown on Fig. 2. An alternating supply 1 of frequency N is coupled by a transformer 5 with an oscillating circuit comprising in series a 60 condenser 2 having a capacity C and a coil 4 provided with a magnetic core and having an inductance L in the straight part of its characteristic curve (i. e. when its core is not saturated).

65 This coil is short circuited by the switch 3.

The apparent inductance due to the supply will be supposed equal to L' .

The frequency of the free fundamental oscillations of this circuit, the iron not being saturated, is:

$$\frac{1}{2\pi\sqrt{(L+L')C}}$$

and that of its harmonics is:

$$\frac{K}{2\pi\sqrt{(L+L')C}}$$

K being an integer.

If the frequency N of the alternating supply A is equal to that of one of these harmonics that is if

$$N = \frac{K}{2\pi\sqrt{(L+L')C}}$$

or

$$(L+L')C \times 4\pi^2 \left(\frac{N}{K}\right)^2 = 1$$

there is resonance and the fundamental oscillation of frequency $\frac{N}{K}$ will be kept up in the circuit together with its harmonics.

To set the circuit oscillating freely it is sufficient to suddenly modify the electrical constitution of the circuit; thus the coil 4 can be short-circuited by means of the switch 3 which is thenafter reopened. The current is cut off by the switch at its passage through zero that is when the voltage of the condenser is at its lowest.

To use the desired alternating current having a frequency $\frac{N}{K}$ the primary of a transformer 6 having an inductance L_1 is preferably connected with the terminals of the condenser 2'.

The condition for resonance will then be:

$$\frac{(L+L')L_1}{L+L'+L_1} C \times 4\pi^2 \left(\frac{N}{K}\right)^2 = 1$$

the term due to the inductance being modified by the action of the inductance L .

The current produced at the terminals of the secondary of the transformer 6 by the fundamental wave for instance will have the desired demultiplied frequency $\frac{N}{K}$. The other waves may be eliminated as well known in the art by suitable filters.

What I claim is:

1. Frequency reducing arrangement comprising a circuit adapted to oscillate freely at a fundamental frequency and at the harmonics thereof, a supply of alternating current the frequency of which is equal to that of one of these harmonics, and adapted to keep up the said harmonic, means for starting the free oscillations of the circuit and

its harmonics and means for selecting the desired oscillations.

2. Frequency reducing arrangement comprising a circuit adapted to oscillate freely at a fundamental frequency and at the harmonics thereof, a supply of alternating current the frequency of which is equal to that of one of these harmonics and coupled with the said circuit, means for starting the free oscillations of the circuit, means for selecting the desired oscillations, and a utilization circuit coupled with the oscillating circuit.

3. Frequency reducing arrangement comprising a circuit adapted to oscillate freely at a fundamental frequency and at the harmonics thereof, an induction coil inserted in the said circuit and provided with a magnetic core adapted to be saturated by a current weaker than that due to the free oscillations of the circuit, a supply of alternating current the frequency of which is equal to that of one of these harmonics and coupled with the said circuit, means for starting the free oscillations of the circuit, means for selecting the desired oscillations, and a utilization circuit coupled with the oscillating circuit.

4. Frequency reducing arrangement comprising a circuit adapted to oscillate freely at a fundamental frequency and at the harmonics thereof, an induction coil inserted in

the said circuit and provided with a magnetic core adapted to be saturated by a current weaker than that due to the free oscillations of the circuit, a switch adapted to short circuit the said coil, a supply of alternating current the frequency of which is equal to that of one of these harmonics and coupled with the said circuit, means for selecting the desired oscillations, and a utilization circuit coupled with the oscillating circuit.

5. Frequency reducing arrangement comprising a circuit adapted to oscillate freely at a fundamental frequency and at the harmonics thereof, an induction coil inserted in the said circuit and provided with a magnetic core adapted to be saturated by a current weaker than that due to the free oscillations of the circuit, a switch adapted to short circuit the said coil, a condenser in said circuit, a second coil inserted in parallel with the said condenser, a supply of alternating current the frequency of which is equal to that of one of these harmonics and coupled with the said circuit, means for selecting the desired oscillations, and a utilization circuit coupled with the oscillating circuit through the coil inserted in parallel with the condenser.

In testimony whereof I have affixed my signature.

JEAN GUSTAVE FALLOU.
